UNITED STATES PATENT OFFICE.

LOUIS H. ENGELHARDT, OF EVERETT, MASSACHUSETTS, ASSIGNOR OF ONE-HALF TO HARRY M. MCNELLY, OF SAME PLACE, AND MARK GALLERT, OF WATERVILLE, MAINE.

ELECTROMAGNET-MOTOR.

SPECIFICATION forming part of Letters Patent No. 673,980, dated May 14, 1901.

Application filed June 22, 1900. Serial No. 21,131. (No model.)

To all whom it may concern:

Be it known that I, LOUIS H. ENGELHARDT, of Everett, in the county of Middlesex and State of Massachusetts, have invented a new and useful Electromagnet-Motor, of which the following is a specification, reference being had to the accompanying drawings, in which—

Figure 1 is a diagram of an electromagnet-motor embodying one form of my invention. Fig. 2 is a diagram of that form of my invention shown in Fig. 1, but showing the relation of the parts after a change of polarity takes place in one group of the armature-magnet, as hereinafter described. Fig. 3 is a longitudinal sectional view of a motor embodying my invention, showing it in form equipped for use. Figs. 4 and 5 are detail views of the armature-magnets and fixed magnets, respectively, hereinafter more fully described.

My invention is an electromagnet-motor comprising a number of fixed magnets, an armature made up of a number of magnets separated from and out of contact with the fixed magnets and arranged to traverse the fields of the latter, and means controlled by the armature for automatically reversing the direction of the current through some of the magnets of the armature independently of the other magnets of the armature as the former pass the fixed magnets and while the other magnets of the armature are between the fixed magnets, so that when the motor is in operation the fixed magnets and some of the armature-magnets are always exerting both their attractive and repelling force to move the armature in the same direction and also so that none of the magnets of the motor are ever acting to oppose the movement of the armature.

In the drawings, Fig. 1 shows a diagram of one form of my invention wherein the armature is represented as made up of two groups of electromagnets $a a'$ and $b b'$ and the fixed or stationary magnets as comprising magnets $c c'$. One end of the coil a^3 of magnet a is connected by wire a^3 with brush a^4 , and the other end of coil a^3 is connected by wire a^5 with one end of the coil a^6 of magnet a' , the

other end of coil a^6 being connected by wire a^7 with brush a^8 . One end of the coil b^2 of magnet b is connected by wire b^3 with brush b^4 , and the other end of coil b^2 is connected by wire b^5 with one end of coil b^6 , the other end of which is connected by wire b^7 with brush b^8 . Thus it will be clear that the armature is made up of two groups of electromagnets $a a'$ and $b b'$ and that the magnets of each group are in series, and it will also be clear from Fig. 1 that alternate magnets of one group are of opposite polarity to the other magnets of that group and also that alternate magnets of the group of fixed magnets are of opposite polarity to the other magnets of that group.

In that form of my invention shown in Fig. 3 the magnets $c c'$ are fixed—that is, they are fast to a stationary ring B , secured to base C and arranged in a circle around shaft A —and the magnets of the armature are also arranged in a circle around shaft A , as will be clear from Figs. 4 and 5; but the armature-magnets are mounted on a head D , fast to shaft A , and rotate on the axis of shaft A . To head D are also fast arms $d d$, which carry the brushes $a^4 a^8$ and $b^4 b^8$, so that when head D revolves said brushes move with it and travel around the rings of the commutator E , which are stationarily supported by a bracket e , fast to one of the standards $F F$. The segments which make up the rings of the commutator E are divided into two groups, one group, composed of segments $e' e'$, being connected with the positive line-wire G by wire g and the other group, composed of segments $e^2 e^2$, connected with the other line-wire G' by wire g' , and the segments of the rings are so arranged that those of one group alternate, as it were, with those of the other group, (see Figs. 1 and 2,) so that when the brushes are carried around the rings the direction of the current passing through the coils of magnets $a a'$ and $b b'$ is reversed. The segments $e' e' e^2 e^2$ are also arranged relatively to the fixed magnets $c c'$, so that while one of the magnets of the armature is approaching a fixed magnet the proximate poles of those two magnets are maintained unlike, and they tend to attract

one another; but when the armature-magnet has reached the fixed magnet its poles are changed by the commutator E, so that said magnets repel each other, and the poles of the armature-magnet are not again changed until it reaches the next fixed magnet. Thus it will be clear that so long as an armature-magnet is between two of the fixed magnets its polarity is opposite to that of the fixed magnet which is in advance of it, and those two magnets attract each other, and that it is of like polarity to the fixed magnet which it has just passed, and that those two magnets repel each other.

15 It will also be clear from Figs. 1 and 2 that when the magnets of one group of armature-magnets are in line or in coincidence with the fixed magnets each armature-magnet of the other group is between the fixed magnets, so 20 that although one group of the armature-magnets is temporarily inactive, owing to their position opposite the fixed magnets, the other group of armature-magnets is in service.

It is within the scope of my invention to 25 have the magnets *a a'* and *b b'* stationary and the magnets *c c'* revolve; but I prefer the form herein shown, which I consider the best.

What I claim as my invention is—

1. An electromagnet-motor comprising a 30 number of fixed magnets; an armature made up of a number of magnets separated from and out of contact with the fixed magnets and arranged to traverse the fields of the latter; and means controlled by the armature for automatically reversing the direction of the current through some of the magnets of the armature independently of the other magnets of the armature as the former pass the fixed magnets and while the other magnets of 35 the armature are between the fixed magnets.

2. An electromagnet-motor comprising a group of fixed magnets; an armature made up of two groups of magnets separated from and out of contact with the fixed magnets 40 and arranged to traverse the fields of the latter; and means controlled by the armature for automatically reversing the direction of

the current through the magnets of one group of armature-magnets independently of the magnets of the other group as the former pass 50 the fixed magnets and while the magnets of the other group are between the fixed magnets.

3. An electromagnet-motor comprising a group of fixed magnets with the alternate magnets of that group of one polarity and the other magnets of that group of opposite polarity; an armature made up of two groups of magnets separated from and out of contact with the fixed magnets and arranged to traverse the fields of the latter, and with the alternate magnets of each group of opposite polarity to the other magnets of the group, and also with the magnets of the two groups alternating; and a commutator controlled by the armature for reversing the direction of the 65 current through the magnets of one group of armature-magnets independently of the other group as the former pass the fixed magnets and while the magnets of the other group are between the fixed magnets. 70

4. In an electromagnet-motor, in combination, fixed magnets *c, c'*; the two groups of movable magnets *a, a'* and *b, b'* opposite the fixed magnets; shaft A on which said magnets *a, a'* and *b, b'* are mounted; and means controlled by shaft A for reversing the direction of the current through one of the groups *a, a'* or *b, b'* without reversing the current through the other group, and as the former pass the fixed magnets *c, c'*, substantially as described. 75

5. In an electromagnet-motor, in combination, fixed magnets *c, c'*; the two groups of magnets *a, a'* and *b, b'* opposite the fixed magnets; shaft A on which said groups *a, a'* and *b, b'* are mounted; and commutator E, substantially as described. 80

In testimony whereof I have signed my name to this specification, in the presence of two subscribing witnesses, this 16th day of May, A. D. 1900.

LOUIS H. ENGELHARDT.
